UNITED STATES PATENT OFFICE.

BENJAMIN BASSKIN AND ABRAHAM WAISMAN, OF ST. LOUIS, MISSOURI.

UNDERPRESSER.

Application filed November 17, 1920. Serial No. 424,677.

To all whom it may concern:

Be it known that BENJAMIN BASSKIN and ABRAHAM WAISMAN, citizens of Czechoslovakia and of the United States, respectively, and residents of the city of St. Louis and State of Missouri, have invented certain new and useful Improvements in Underpressers, of which the following is a specification containing a full, clear, and exact description, reference being had to the accompanying drawings, forming a part hereof.

This invention relates to improvements in under pressers and has for its primary object a device for pressing the seams of garments before the garments are lined, the pressing being accomplished by reversible power driven rollers which feed the garment in either direction so that one seam can be pressed while feeding the garment into the machine and another while feeding it out.

A further object is to construct an under presser having reversible power-driven pressing rollers, the upper presser rollers being heated and provided with an adjustable tension so that the pressure of the rollers can be increased or decreased at will.

A still further object is to construct an under presser having power-driven pressing rolls and a seam spreader, which spreads the free edges of the seam and at the same time moistens them before they pass between the pressing rollers.

In the drawings:

Fig. 1 is a side elevation of our device with portions thereof broken away and in section.

Fig. 2 is a vertical longitudinal sectional view of the same.

Fig. 3 is an enlarged view showing the manner of driving the lower rolls.

Fig. 4 is an enlarged view showing the mechanism by which the upper rolls are driven.

Fig. 5 is a sectional view of one of the upper rollers showing one method of heating the same.

Fig. 6 is a top plan view of the spreader.

Fig. 7 is a vertical longitudinal sectional view of the same.

Fig. 8 is a side elevation of the spreader showing the manner in which the edges of the seam are turned down prior to pressing.

In the construction of our device we employ a head composed of the hollow vertical member 9 and two parallel members 10

and 11. One of these members is positioned directly above the other so as to form substantially a U-shaped head. Through the upper member 10 projects a shaft 12, which is provided near its front end with the worm 13 and near its opposite end with the crank 14. The end of the shaft 12 adjacent the crank 14 extends through the vertical portion 9, and is provided on its projecting end 65 with a fly wheel 15 and a sheave wheel 16. Over this sheave wheel passes a belt 17, this belt also passing around the sheave wheel 18 mounted beneath the table 19. The sheave wheel 18 is secured to a shaft 20, which is 70 supported in hangers 21. On the shaft 20 are also mounted friction cones 22 and 23. These cones are held against rotation on the shaft in any well known manner, but are permitted to slide longitudinally thereon. 75 Between the cones 22 and 23 is a groove collar 24 in which the fork end 25 of the shift lever 26 is secured. The shift lever 26 is pivotally mounted at its lower end in a bracket 27. Connected to the shift lever 26 is one 80 end of a shifter rod 28, its opposite end being connected to the double foot lever 29. This foot lever is pivotally mounted in a bracket 30 and is so arranged that by pressing on either of the projecting portions 31, the 85 cones 22 and 23 are brought in contact with the cone 32. This cone is secured to a motor 33, or it may be secured to any other suitable source of energy or power. Meshing with the worm 13 is a worm gear 34, which is 90 secured to one end of a vertical shaft 35. The lower end of this shaft is provided with a key 36, and over the shaft and key is placed a sleeve 37, which has the beveled gear 38 formed on the lower end thereof. 95 This beveled gear 38, in turn, meshing with the beveled gear 39, which is mounted on the shaft 40. Secured to the shaft 40 is a spur gear 41, which, in turn, meshes with the spur gears 42 mounted on the shafts 43 100 of the upper rollers 44. These upper rollers are formed hollow, as indicated in Fig. 5, and when electrically heated are provided on their interior with the heating coil 45, the ends of the heating coil being attached 105 to contact rings 46 and 47, which are mounted on a core 48. This core is of insulating material and is secured to the shaft 43. Contacting with the rings 46 and 47 are brushes 48a and 49, which brushes are connected to 110 conductors 50, the conductors in turn entering the switch 51 so that the electric cur-

rent can be shut off from the rollers, when desired.

I may also utilize gas or steam for heating the upper rollers without departing from the spirit of our invention. The shafts 43 are mounted in a sliding frame 52. This frame being slideable vertically in the downward extension 53 formed integral with the projection 11. Secured to each of the shafts 43 is a yoke 54, and from this yoke is a vertical extension 55. To this vertical extension is secured a cross bar 56, which is provided at its central portion with an eye 57 through which the link 58 is secured. The link 58 is also secured to the end 59 of a lever 60. This lever being pivoted in the ear 61. To the opposite end of the lever 60 is secured a cable 62. This cable passes around the roller 63, which is mounted beneath the table 19 and has its opposite end secured in a lever 64, which is mounted in a bracket 65. This bracket is also secured to the bottom of the table and when the lower end of the lever 64 is moved toward the rear of the machine by the knee of the operator, the lever 60 is operated and the rollers 44 are raised, thus permitting the insertion of the garment to be pressed. Surrounding each of the vertical projections 53 and above the cross bar 56 is a coil spring 66. The upper end of this coil spring contacting with the lower end of the adjusting screw 67. This adjusting screw is screw threaded in the upper portion of the member 10 and is for the purpose of increasing or decreasing the tension. Pivotally secured to the member 52 is a spreader 68. This spreader has two of its sides so shaped as to provide a central upwardly inclined edge 69 and two horizontally inclined edges 70,—this is for the purpose of spreading the free ends or edges of the seam, as illustrated in Fig. 8. Connecting the seam spreading edges of the spreader are parallel vertical walls 71. These walls are provided with upwardly projecting extensions 72 and 73, by means of which the spreader is secured in position. The projection 73 is provided with notches with which a spring 74 engages, this spring being used to hold one of the spreading edges in contact with the cloth when the device is being operated. Secured near the apex of the spreader is a wall 75,—this wall forming a compartment in which absorbent material 76 is placed. This absorbent material is adapted to receive moisture through the pipes 78. These pipes are connected together by a pipe 79, which is provided at its center with an upwardly projecting funnel 80 and into this funnel one end of a moisture pipe 81 is placed, the opposite end of the pipe being secured within the water reservoir 82. The purpose of placing the funnel on the pipe 79 is to permit the admis-

sion of water therein when the spreader is tilted the pipe 79 will also be tilted and feed the water to the depressed end of the spreader and shut off the water from the raised end. This construction eliminates the use of a two-way valve. Secured in the member 11 is a shaft 83. This shaft is mounted in bearings formed integral with the head and is provided near its front end with a worm 84. This worm meshes with the worm gears 85 formed on the lower end rollers 86. These feed rollers also have bearing in the member 11. The opposite end of the shaft 83 is provided with a crank 87. The crank 87 and crank 14 are connected together by means of the connecting rod 88, which places both shafts in operation simultaneously and at the same rate of speed. We may also, if desired, use a gear or chain drive instead of connecting rod 88 to place these two shafts in rotation without departing from the spirit of our invention. We may also place a covering of felt or other fabric around the rollers 44 and 86, if found desirable or necessary. The rollers 44 and 86 are so placed as to give a minimum fluting effect when the garment is being pressed. This is accomplished by having the rollers 86 smaller than the rollers 44 and arrange them so that the garment will pass between the rollers in substantially a straight line, the deviation from the straight line being so slight as to have no appreciable fluting effect on the fabric.

The operation of my device is as follows: The source of heat to the upper rollers is turned on and the rollers heated, the water container filled with water, and the device is then ready for operation,—the operator presses the lever 64, which raises the top rollers and permits the insertion of the garment; that portion of the seam which is first placed beneath the rollers is arranged by hand and the pressure on the lever 64 released, then the forward end of the spreader is depressed and the foot lever 29 so operated as to place the machine in operation and feed the garment into the machine. When the garment has been fed into the machine it is turned and another unpressed seam brought to the upper face of the member 11; the rollers are then raised, the garment placed underneath the rollers, the spreader tilted in the operation direction and the foot lever depressed in the opposite direction. This movement will simultaneously press the seam and feed the garment out of the machine.

Thus it will be seen that by the operation of our device a great deal of time is saved in pressing the seams and a more uniform heat and uniform pressing of the seams accomplished than where the work is done by hand. Furthermore, by the use of our device an unskilled operator can press the

seams and also the ability of the operator to turn out work will not be limited by his strength as is at present the case where the heavy irons must be used and manually operated.

You may also, if desired, set the rollers so that their axis will be parallel to the extensions 10 and 11. In this construction the machine is used for pressing seams in 10 arm holes and similar work. This, however, involves no departure from the principle of our operation.

Having fully described our invention what we claim is:

15 1. An under presser comprising a head having two horizontal portions, the lower horizontal portion being free and unobstructed so that a completely sewed garment may be inserted thereover, power-driven 20 rollers mounted in each of said horizontal portions, means for heating some of said rollers, means for placing said rollers in operation simultaneously, and means for reversing the direction of rotation of the 25 rollers.

2. An under pressure comprising a head, having a vertical and two horizontal portions, the lower horizontal portion being free and unobstructed so that a completely sewed garment may be inserted thereover, a shaft mounted in each of said horizontal portions, said shafts being so connected as to revolve simultaneously, rollers mounted in each of said portions and operable with the 30 shafts, means for heating one set of said rollers, means for lifting one set of said rollers from contact with the other set, a spreader carried by said head, means for operating the rollers, means for reversing the operation 35 of said rollers, and means for supplying moisture to the spreader.

3. An under presser comprising a head, having a vertical portion, an upper and lower horizontal portion formed integral 40 therewith, a shaft located in each horizon-

tal portion, a crank formed on each shaft, a connecting rod secured to said cranks, rollers mounted in the lower horizontal portion and adapted to be driven by the lower shaft, rollers adjustable vertically carried 50 by the upper horizontal portion and operable by the upper shaft, means for imparting tension to the upper roller, means for heating the upper rollers, means for raising the upper rollers out of contact with the lower 55 rollers, a spreader carried by the upper horizontal portion, means for supplying moisture to the spreader, and means for controlling the direction of rotation of the rollers.

4. In a seam pressing device, feeding means, means to open and spread the members of the seam while being fed, means to flatten the spread seam members, means to dampen the seam members, and a heated 60 65 pressing element to finally press the dampened, flattened seam members.

5. In a pressing machine for sleeves or the like, a base member, an arm extending therefrom arranged to be slipped into a 70 sleeve, a pressing device located adjacent the arm arranged to press the seam of a sleeve on the arm, feeding means to advance a sleeve longitudinally of the arm during a pressing operation, and means located adjacent the pressing device to dampen the 75 seam to be pressed.

6. In a seam pressing device, a plurality of cooperating pressing rollers, and means to spread the members of a seam, all 80 arranged so that said spreading means will separate the members of a seam, after which one of said rollers will preliminarily flatten the seam, the last roller being adapted to press the seam, said last roller being heated, 85 and means to feed the goods to be pressed.

In testimony whereof, we have signed our names to this specification.

BENJAMIN BASSKIN.
ABRAHAM WAISMAN.
